UNITED STATES PATENT OFFICE.

DANIEL BLOMBACH, OF KEENE, NEW HAMPSHIRE.

ATTACHMENT FOR LOOMS.

1,334,074.

Specification of Letters Patent. Patented Mar. 16, 1920.

Application filed May 20, 1919. Serial No. 298,453.

To all whom it may concern:

Be it known that I, DANIEL BLOMBACH, a citizen of Germany, and a resident of Keene, in the county of Cheshire and State of New Hampshire, have invented certain new and useful Improvements in Attachments for Looms, of which the following is a specification.

The present invention relates to attachments for looms of the narrow-ware type, whereon ribbons, tapes, etc., are woven. The invention pertains more particularly to a loom attachment for working patterns or figures in the face of the fabric, while it is being woven.

The main object of the invention is to provide an attachment of the character described, which is simple in construction, efficient in operation, and which can be mounted on a loom of the type mentioned without necessitating material changes in the construction of the latter.

A further object of the invention is to so construct the attachment that the fabric-making weft serves at the same time to entwine or bind down in the face of the fabric a plurality of pattern- or figure-threads, that run substantially parallel to the weft.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:

Figure 1 is a transverse vertical section taken through a loom provided with the attachment; Fig. 2 is a plan view of the attachment on a larger scale; Fig. 3 is a section taken on line 3-3 of Fig. 2; Fig. 4 is a plan view of a portion of the attachment, on a still larger scale; Fig. 5 is a view similar to the one shown in Fig. 4 with the elements in other positions; Fig. 6 is a section taken on line 6-6 of Fig. 5; and Fig. 7 is a view, in plan, of a piece of figured fabric

produced upon a loom provided with the attachment.

In the drawings only as much of the loom has been shown as is necessary to understand the invention, and, while herein a particular type of a loom has been disclosed for purposes of illustration, the invention is applicable to other types just as well.

In the drawings, the numeral 10 indicates the frame of the loom, to which are pivoted at 11 lay-swords 12, carrying a batten 13 of any suitable construction. This batten is actuated from the main shaft 14 of the machine, by forming upon the said shaft a 70 crank, connected by a pitman 15 with the said batten, thereby causing the latter to move back and forth, in the usual manner, to beat up the filling. The harness frames, denoted by the numerals 16 and 17, are actuated by means not shown, to raise or lower the same in forming sheds. The attachment herein described is illustrated for working patterns or figures in the face of a plain-weave fabric, and the sheds are thus controlled and opened in the usual manner according to the weave mentioned. It is to be understood, however, that the invention is not limited to this particular weave. The loom frame is provided with warp beams 18, 80 from which the warps are led over suitable warp rolls 19 to and through the usual eyes in whatever heddles are carried by the harness frames, and thence between the dents of the usual reed 20 upon the batten 13. The woven ribbons are led over a roller 21, carried by the breast beam 22, and are then taken care of by any suitable take-up mechanism, common to looms. The shuttle 23 is of the fly-shuttle type, and is actuated by 95 means herein not shown, as the same does not form part of the present invention, it being actuated at each pick of the loom.

The elements so far described operate in the usual manner, so that a detailed description of the operation seems to be unnecessary.

In order to properly understand the construction of the attachment, it seems to be indicated first to describe the fabric woven 105 on a loom provided therewith. This fabric is shown in detail in Fig. 7 of the drawings, and comprises a plain-weave body fabric 24, having warp threads 25 and weft threads 26. Into the face of this fabric are 110 worked patterns or figures 27, the threads of each pattern being entwined or bound down

by the weft of the base fabric, the pattern- or figure-threads running substantially parallel to the weft. The base fabric is produced by the loom in the ordinary manner, 5 while the pattern- or figure-threads are presented for entwining by the attachment that forms the subject matter of the present application for Letters Patent. In Fig. 7 three pattern- or figure-threads are shown, 10 but it is obvious that any suitable number may be employed according to the requirements. Each of these threads is wholly disposed upon the outer face of the fabric and produces a zigzag pattern that extends 15 longitudinally of the ribbon. These threads may be obviously of any suitable color, they being led to the attachment from bobbins 28, that are mounted upon the loom frame.

The attachment comprises, generally 20 speaking, two parts, one, denoted by the numeral 29, being mounted upon the batten, and the other one, indicated at 30, being held upon the breast beam 22. The element 25 30 comprises a dobby-chain mechanism, including a prism 31, that is rotatably mounted in standards on the loom frame and is actuated in any suitable manner by a mechanism so that at every pick of the loom it is given a partial turn, to present another 30 pattern card 32 to the mechanism 29, carried by the batten. The pattern cards carry each three pegs 33 or, in other words, as many pegs as there are pattern- or figure-threads 27 employed. The pegs are of different lengths, for a purpose that will hereinafter appear.

The mechanism 29 comprises three slides 34, which are mounted in guides 35 upon the base plate 38, the latter being disposed 40 horizontally and fixed to the front of the batten. These slides coöperate with the pegs 33, they being caused to move by the pegs toward the batten and in the opposite direction by springs 39. With each slide 45 coöperates one spring coiled upon a fixed spindle 40 in a recess 41 in the respective slide. With each spring co-acts a stop 42, held stationary by screws 43 upon the base plate 38. Each slide is connected, by means 50 hereinafter to be described, with a horizontally disposed bar 44; that extends parallel to the batten and is adapted to reciprocate longitudinally of the batten or, in other words, transversely of the direction of travel of the wrap threads. Each of these 55 bars carries a downwardly projecting needle 45, having an eye in its free end, through which a figure- or pattern-thread 27, leading from the bobbins 28, is threaded. These needles reach within the sheds in rear 60 of the shuttle, when the batten is in its outermost position (that is away from the breast plate), but are disposed above the threads when the batten is in its inner position, in which it beats up the filling at the

70 fell of the ribbon. The connection between each bar 44 and the respective slide 34 is made by a lever 46 and two links 47. The lever 46 is fulcrumed at 48 to the base-plate 38, the two links being pivoted to the said lever and the slide and bar, respectively.

To the upper face of each slide 34 is fixed a longitudinally extending toothed rack 49, having ratchet-like teeth. With each of these racks coöperates a pawl 50, the said 75 pawls being oscillatably mounted upon a cylindrical bar 51, that is held by standards 52 a substantial distance above the slides, the standards being fixed to the base plate 38. These pawls are kept by gravity in engagement with the teeth of the racks 49, permitting the slides to move toward the batten and holding the springs 39 under compression, as will hereinafter appear, to cause the slides to move in opposite directions when the pawls are disengaged from the racks. For disengaging the said pawls, there is pivoted to the bar 51 a frame 53, having a transversely extending member 54 disposed below and abutting against the 80 said pawls. To this frame is fixedly attached a rearwardly extending arm 55, that is disposed in the path of a finger 56, the latter being fixed to a shaft 57, that is rotatably mounted in the loom frame and is 85 driven from the main shaft by a train of gears 58. This train of gears is so designed that the shaft 57 makes one turn for every two revolutions of the main shaft.

The operation of the machine is as follows:—The batten is reciprocated in the usual manner from the main shaft, the reed beating up the filling upon each forward movement of the batten and the shed opening on each backward movement thereof. The mechanism 29 travels with the batten. Let us suppose that the batten was just in its outermost position, the shuttle has traveled through the shed and after that the finger 56 has raised, by the intermediary 105 of the arm 55, the frame 53. The pawls have thus been disengaged from the slides, which, under the action of the springs 39, coöperating therewith, have moved forward, that is to say toward the breast beam of the machine. A rocking bar 59 takes up the slack of the figure-threads 27, while the batten moves forward. While the batten moves forward, to beat up the filling, the prism 31 is given a partial turn to present the next 110 pattern card in the series to the slides. The pegs, brought into registering positions with the slides, after the same have been released as stated, are short pegs, whereby the slides will move forward, when coming into contact with the pegs, a short distance only, thereby causing the bars 44 to move a short distance in the direction of the arrow shown in Fig. 2 of the drawings, bringing their 115 needles into the positions indicated by the 120 125 130

reference character A upon Fig. 7 of the drawings. The pawls keep these needles in position as the batten now moves backward and the shed opens. The needles project, 5 as above stated, into the shed, when the batten is in its rear position (Fig. 1). The shuttle moves then through the shed, the weft engaging the threads 27, which are beaten up with the filling on the next forward stroke of the batten. Inasmuch as the needles are, before reaching the forward position of the batten, disposed above the warp threads, the threads 27 are located on the outer face of the batten. When the batten, 10 on its forward stroke, reaches its outermost position, the prism has already been given a partial turn, and longer pegs presented to the slides, which will thus move forward and cause the needle carrying bars 15 44 to move farther in the direction of the arrow shown in Fig. 2 of the drawings, stopping at points indicated by the reference character B on Fig. 7 of the drawings. The batten moves then backward, the shuttle 20 being actuated as above described. Before the batten moves again toward the jacquard mechanism, the finger 56 lifts the arm 55, thereby disengaging the pawls from the racks on the slides, so that the latter 25 move forward under the action of the springs associated therewith. When coming into contact with the next pattern card, short pins are in position to bring the needles into the positions indicated by the 30 reference character C in Fig. 7 of the drawings. The cycle of operation is then repeated.

From the foregoing it appears that the jacquard mechanism and the slide releasing mechanism are so timed that the slides are released by the pawls at every second pick of the loom, and the slides, after being released, come into contact with short pegs and at the next pick with long pegs on the 35 pattern cards. In this manner the figure-thread carrying needles are moved in a zig-zag line, the positions of the sharp turns of the zigzag line being determined by the size of the pegs on the pattern cards.

It is obvious that, while herein three 40 slides and a corresponding number of cooperating parts have been described, any other suitable number may be used according to the requirements. Attention is further called to the fact that, while herein 45 the loom has been described as producing a single ribbon only, in practice a great

number of these ribbons will be made on a single loom, each bar 44 carrying in such case a corresponding number of needles. 60

What I claim is:—

1. In a loom, the combination with the shed-forming mechanism, weft introducing shuttle and batten of the loom, of a bodily stationary rotatable prism and peg carrying 65 pattern cards of a dobby-chain mechanism mounted in front of said batten, a plurality of figure-thread needle-carriers reciprocably mounted on said batten on top of the shuttle support, said needle-carriers moving 70 longitudinally of the batten, slides upon said batten actuated by the pegs of the dobby-chain mechanism, and connecting means between said slides and said needle-carriers. 75

2. In a loom according to claim 1, the needles on said carriers extending into the shed when said batten is in its outer position and being disposed above the fabric when said batten is in its inner position. 80

3. A loom according to claim 1, including a spring associated with each slide for moving the same in a direction opposite to that produced by said pegs. 85

4. A loom according to claim 1, comprising a rack upon each slide having ratchet teeth, a pawl coöoperating with each rack, a pivoted frame carrying said pawls, said pawls preventing a movement of said slides in a direction opposite to that induced by 90 said pegs, a rotary shaft carrying a lug coöperating with said frame for raising the latter so as to disengage said pawls from said racks at times when said batten starts its movement toward said pattern cards. 95

5. A loom according to claim 1, comprising a rack upon each slide having ratchet teeth, a pawl coöoperating with each rack, a pivoted frame carrying said pawls, said pawls preventing a movement of said slides 100 in a direction opposite to that induced by said pegs, a rotary shaft carrying a lug coöperating with said frame for raising the latter so as to disengage said pawls from said racks upon every second pick of the 105 loom at times when said batten starts its movement toward said pattern cards.

Signed at Keene, in the county of Cheshire and State of New Hampshire, this 15th day of May, A. D. 1919.

DANIEL BLOMBACH.
